(21) Appl. No.: **29/143,528****(57) CLAIM**(22) Filed: **Jun. 15, 2001**

The ornamental design for a flexible cable manager, as shown and described.

(51) LOC (7) Cl. .... **08-05****DESCRIPTION**(52) U.S. Cl. **D8/356**

FIG. 1 is a bottom view of the flexible cable manager embodying my design;

(58) Field of Search **D8/354, 349, 355,**

FIG. 2 is a side elevational view thereof illustrating the flexible cable manager secured to an underside of a mounting structure as indicated in dash-dot lines, and illustrating a cable as indicated by dotted lines projecting into and out of the flexible cable manager. An elevational view taken from any point around the flexible cable manager will be identical to this view.

D8/356, 358, 360.1, 368, 394, 395, 396,

300, 307, DIG. 2; 24/115 R, 129 B, 129 D,

129 R, 335, 336, 339, 115 H, 115 K, 115 M;

248/49, 58, 309.1, 61, 317, 51, 65; 211/87.01;

206/701; D6/512, 546; D26/26, 72; 242/388,

388.1, 406

FIG. 3 is a sectional elevational view thereof taken along line 3—3 in FIG. 1

FIG. 4 is a perspective view, taken from above, and illustrating the interior of the flexible cable manager.

FIG. 5 is a side elevational view thereof secured on top of a horizontal mounting structure; and,

FIG. 6. is a side elevational view thereof secured on a vertical mounting structure.

In the drawings, the structures depicted by dotted lines or dash-dot lines are solely for environmental purposes, and do not constitute part of the present invention.
